ELECTROSTATIC COATING APPARATUS

Edwin M. Ransburg, Indianapolis, Ind., assignor,
by direct and mesne assignments, to Ransburg
Electro-Coating Corp., Indianapolis, Ind., a
corporation of Indiana

Application November 19, 1945, Serial No. 629,608

9 Claims. (Cl. 91—18)

1

This invention relates to the treatment of articles in an electrostatic field and relates, in particular, to an improved apparatus for preventing hazardous conditions in the treating zone.

In the treatment of articles in an electrostatic field the voltage used and spacing of electrodes to articles is such as to avoid development of a spark between the electrodes and the articles being treated. A reduction of the spacing used for effective treating of the articles may result in a spark, and breakdown of the electrostatic field in the vicinity of the spark that would interfere with proper treatment of the article, and might also ignite any inflammable vapors in the vicinity. This might occur, for example, if an object which is being treated or an extraneous object falls on to the electrode and reduces the distance between the electrode and the objects being treated to that at which a spark would occur, or creates a physical obstruction to the passage of objects to be treated through the treating zone.

An object of this invention is to provide an apparatus for electrostatically treating articles on a conveyor which is constructed to stop operation of the conveyor, with or without deenergizing the electrostatic field when an abnormal condition occurs in the treating zone.

Another object of this invention is to provide an apparatus for electrostatically treating articles in which a warning signal is actuated when an abnormal condition occurs in the treating zone.

Another object of this invention is to provide an apparatus for electrostatically treating articles in which the occurrence of an abnormal condition in the treating zone deenergizes an electrical circuit.

A further object of this invention is to provide an apparatus for electrostatically coating or detearing objects which embodies a mass actuated switch to stop the conveyor carrying the articles to be treated, deenergize the electrodes and actuate a signal when an object falls on the electrode, or may accomplish any one or all of the above functions.

The invention will be described in greater detail in connection with the accompanying drawings in which is illustrated preferred embodiments of the invention by way of example, and wherein:

Figure 1 is a perspective view of an electrostatic coating apparatus embodying my invention,

Figure 2 is a cross sectional view of a detail,

Figure 3 is a wiring diagram of the electric cir-

2

cuit for the embodiment illustrated in Figure 1, and

Figure 4 is a perspective view of a modification embodying my invention.

Referring to Figure 1 there is schematically shown a conveyor 10 of any suitable construction on which the articles 11 to be treated, shown here as cylindrical containers, are supported by suitable hangers 12. Any suitable atomizing means 13, shown here schematically, may be employed such as, for example, a type employing converging air and liquid streams, and such atomizing means is arranged in a suitable position adjacent the articles to direct a stream of finely divided coating material toward the articles. An electrode frame 14, shown in the preferred embodiment as comprised of the rectangular panels 15, 16, and 17 made of metal bars welded into a channel shape, is sufficiently rigid to support a plurality of spaced wires 18, which are preferably stretched taut on the frame. The electrode frame 14 is supported by four insulator rods 19 suitably secured thereto. The upper ends of rods 19 are associated with suitably supported switch mechanisms 20 to be later described.

In the modification shown in Figure 1 the taut wires 18 constitute ionizing electrodes and are maintained at a suitable potential difference with respect to the articles to be treated. However, the electrodes may assume any form which produces an ionizing discharge at the potential employed. The conveyor 10 is preferably suitably grounded but, if desired, it may be suitably insulated from ground and connected to the terminal of the electric supply of opposite polarity to the electrodes. The apparatus may be surrounded by a suitable booth (not shown).

The articles 11 to be coated are carried through the coating zone on the conveyor 10, and atomizing means 13 directs a stream of finely divided material into the electrostatic zone to deposit the coating material on the articles. In normal operating arrangement the articles are spaced at a distance from the electrodes farther than that at which a spark will occur, but if this distance is accidentally reduced so that a spark occurs, the spark will cause a breakdown of the electrostatic field and might also cause a fire in the treating zone. The means for eliminating the danger of this condition now will be described.

Referring to Figure 2, a cylindrical member 21 has a threaded extension 22 passing through a hole 23 in a fixed member 24 which may be a part of a spray booth or other supporting structure. A nut 25 threaded on the end of the ex-

tension 22 clamps cylindrical member 21 and plate 26 to the top of the spray booth. Switch housing 20 is secured above the nut at the top of the spray booth by screws 28 passing through spacer 29 and screwed into the switch housing, and lead wires 34 and 35 connect the switch contacts to the terminals of an electric power supply. Push rod 38 passes through the extension 22 into engagement with a spring pressed plunger 39 to actuate the switch contacts. The switch 20 is of a known construction in which a small movement of the switch contacts, on the order of a thousandth of an inch, opens or closes an electrical circuit, and the details of construction therefore need not be described.

Push rod 38 passes through a gland 40 which is threaded into a screw threaded aperture 41 on the inside of the cylindrical member 21, and a compression spring 42 abuts at one end against the upper flat surface of gland 40 and at the other end against the lower flat surface of a flange 43 on push rod 38 to urge the rod upwardly against plunger 39 and hold the switch contacts in engagement. The sensitivity of the apparatus may be adjusted by turning gland 40. When the bias of spring 42 is increased, a greater pull is necessary to pull rod 38 to open the contacts in switch housing 20, and when the bias of spring 42 is decreased a lesser pull is necessary to pull down rod 38 to open the switch contacts. The lower end of rod 38 is suitably secured to insulator post 19, as by a screw threaded connection (not shown), and if desired, a skirt 45 may be provided on the gland 40 surrounding the insulator post 19 to prevent deposition of material on the rod 38.

Referring now to the wiring diagram in Figure 3 there is shown diagrammatically a pair of power supply lines 51 and 52 to which is connected lead wire 34 to a switch mechanism 20. There are four switch mechanisms 20 arranged in series so that the opening of any one of them will deenergize a common electrical circuit, and the actuation of only one switch mechanism need be described in detail. Lead wire 35 connects a switch 20 with one terminal of a relay having a solenoid 54, the other terminal of the solenoid being connected by wire 55 to a switch contact 57. A contact member 58 on the rod 59 of the core 60 bridges contacts 57 and 61, the latter contact being connected by a wire 62 and normally closed manual switch 63 to the supply line 52. Switch 63 is provided to enable the operator to manually cut off the high voltage supply if desired. When switches 20 are closed the current through solenoid 54 attracts the core 60 to the left to hold switch member 58 against contacts 57 and 61, against the bias of a spring 65. A pair of switch members 67, 67' on rod 59 is held in contact with the terminals 68, 68', and 69, 69' in the supply line 71 of the high voltage pack 72. A starting push button switch 75 is provided which is connected by wires 76 and 55 to the terminal of solenoid 54. If desired, the conveyor motor 78 may be connected by wires 80 and 81 into the supply lines 71 of the high voltage power pack to be responsive to switch members 67, 67', or if desired a separate switch may be employed for this purpose. Also, if desired, an alarm actuating switch member 89 may be provided, which upon movement to the right bridges contacts 91 and 92 connected by wires 93 and 94 to the power supply, and containing a suitable alarm signalling device 95.

The operation of the apparatus described is as

follows: When an object falls on the yieldingly supported electrode frame, its weight will exert a downward pull on one of the insulator posts 19 which is transmitted to rod 38 against the bias of spring 42, and rod 38 is thus drawn away from plunger 39 to allow switch 20 to open. This opens the holding circuit of the solenoid 54 which is thus deenergized and allows spring 65 to open switch contacts 67 and 67' which opens the supply line 71 to the power pack 72 to cut off the voltage supply to the electrode 14. At the same time the power circuit 71, 80, and 81 of the conveyor motor is opened to stop operation of the conveyor. Movement of rod 59 to the right also closes switch contacts 89, 91, and 92 to actuate the alarm device 95. The potential of the electrode having been reduced to a safe value, the operator can remove the object from the electrode, which allows the rod 38 to move into contact with plunger 39 to close the switch 20. To resume operation push button 75 is depressed to close the actuating circuit of solenoid 54 through wires 76, 55, 35, switches 20 and wire 34, to pull core 60 to the left thus closing switch contacts 58, 67, and 67', open the alarm circuit and to restore the electrode power supply circuit and conveyor to normal operation condition.

If it is desired to only partially deenergize the electrode the relay may be provided with a second set of contacts engageable by switch members 67, 67' which throws a high resistance into the supply circuit for the high voltage pack 72 to reduce the electrode potential to a safe value. The relay illustrated herein is one example of various mechanical or electronic control devices which may be employed to partially or completely deenergize the electrodes or the conveyor motor, or to actuate an alarm circuit. It is to be understood that reduction of the potential of the electrode to a value such that sparking will not occur, or which will enable the operator to remove the body causing actuation of the alarm without danger, is contemplated within the meaning of the term deenergizing.

In the modification illustrated in Figure 4, a detearing apparatus comprises an expanded metal plate 96 constituting an electrode which is maintained at a suitable potential difference with respect to the articles 11 to be deteared. If desired, an imperforate plate may be used for this purpose. A body falling upon the electrode or excessive accumulation of paint or the like thereon will open a switch 20 to cut off the high voltage supply to the electrode, as described in connection with the wiring diagram in Figure 3.

It is apparent that the alarm device 95 and its circuit may be omitted if desired, also, if desired, wires 80 and 81 may be directly connected to the power supply lines 51 and 52. Various other modifications may be made in the structure and arrangements shown without departing from the invention.

I claim:

1. Apparatus for electrostatically treating an article comprising a support for the article, an electrode movably mounted in spaced relation to the article, means for creating an electrostatic field between the article and the electrode, and means operatively associated with said field-creating means and being responsive to a predetermined movement of said electrode for de-energizing said field.

2. Apparatus for electrostatically coating an article comprising a support for an article, an electrode, yielding means for supporting said

electrode in spaced relation to the article, means for creating an electrostatic field between said electrode and the article, means for introducing finely divided coating material to the electrostatic field, and an electric switch mechanism operatively associated with said field-creating means and said yielding support means and being responsive to a predetermined yielding of said support means for de-energizing said field.

3. Apparatus for electrostatically detearing an article comprising means for applying an excess of liquid coating material to the article, a support for the article coated with excess material, an electrode yieldingly supported in spaced relation to the article, means for creating an electrostatic field between the article and said electrode of sufficient strength to remove excess liquid coating material from the article, and means operatively associated with said field-creating means and being responsive to a predetermined yielding of said electrode for de-energizing the electrostatic field.

4. Apparatus for electrostatically treating an article comprising a support for an article, an electrode spaced from the article, a yielding support for said electrode, a high voltage source for creating an electrostatic field between the article and said electrode, an alarm mechanism, and means operatively associated with said high voltage source and said alarm mechanism and being responsive to a predetermined yielding of said support for de-energizing said field and actuating said alarm mechanism.

5. Apparatus for electrostatically treating an article comprising a conveyor to carry the article, an electrode yieldingly supported in spaced relation to the article, means for creating an electrostatic field between the article and said electrode, an alarm mechanism, and means operatively associated with said conveyor, said field-creating means and said alarm mechanism and being responsive to a predetermined yielding of said electrode for de-energizing said field, actuating said alarm mechanism and stopping said conveyor.

6. In apparatus for electrostatically treating an article including a conveyor for moving the article over a predetermined path and an electrode spaced from said conveyor, the improve-

ment which comprises a movable support for said electrode and means operatively associated with said conveyor and said movable electrode support and responsive to a predetermined movement of said electrode for stopping said conveyor.

5 7. An apparatus for electrostatically treating an article comprising a conveyor for moving the article, an electrode yieldably supported in spaced relation to the article, means for creating an electrostatic field between the article and said electrode, and means operatively associated with said conveyor, said field-creating means and said electrode and being responsive to a predetermined yielding of said electrode for de-energizing said field and stopping said conveyor.

10 8. In apparatus for electrostatically treating an article including a conveyor for moving the article over a predetermined path and an electrode spaced from said conveyor, the improvement which comprises a movable support for said electrode, an alarm mechanism and means operatively associated with said conveyor, said movable electrode support and said alarm mechanism and being responsive to a predetermined movement of said electrode for stopping said conveyor and actuating said alarm mechanism.

15 9. In apparatus for electrostatically treating an article including an electrode spaced from the article and means including an electric circuit for establishing an electrostatic field between the article and said electrode, the improvement which comprises a support for yieldably supporting said electrode, a normally closed switch in said circuit operable to render said field-establishing means inoperative, and means responsive to a predetermined movement of said electrode for opening said switch.
